UNITED STATES PATENT OFFICE.

JOHN GRIMSHAW, OF PATERSON, NEW JERSEY.

DESIGN FOR A HANDKERCHIEF.

SPECIFICATION forming part of Design No. 11,724, dated April 13, 1880.

Application filed February 7, 1880. Term of patent 3½ years.

To all whom it may concern:

Be it known that I, JOHN GRIMSHAW, of Paterson, in the county of Passaic and State of New Jersey, have invented a new and original Design for a Handkerchief, of which the following is a specification.

This invention relates to the new ornamentation of the body of a handkerchief.

The accompanying photograph illustrates my new design.

The body A of the handkerchief contains two series of stripes, *a b*, at right angles to each other. Over the lines *a b* are placed groups B B', composed of long narrow leaves *d*, including slender branches *e* of small leaves and flowers. Groups B B' point in different directions, so that one group points in the direction of a diagonal line joining two of the corners, while the other group points in the direction of the other corners.

The border C may be of any suitable design.

I claim—

1. The design for the body of a handkerchief, which consists of the groups B B', composed of leaves *d* and branches *e*, substantially as described, and shown in the accompanying illustration.

2. The design for the body of a handkerchief, which consists of the lines *a b* and groups B B', composed of leaves *d* and branches *e*, substantially as described, and shown in the accompanying illustration.

JOHN GRIMSHAW.
